[57] CLAIM

The ornamental design for a privacy curtain, as shown and described.

DESCRIPTION

FIG. 1 is a front view of the privacy curtain of the present invention;

FIG. 2 is a back view of the privacy curtain of FIG. 1;
FIG. 3 is a left side view of the privacy curtain of FIG. 1;
FIG. 4 is a right side view of the privacy curtain of FIG. 1;
FIG. 5 is a top plan view of the privacy curtain of FIG. 1;
and,

FIG. 6 is a bottom plan view of the privacy curtain of FIG. 1.

The pattern partially shown in FIGS. 1 and 2 represents a conventional material and is understood to continue across the indicated surfaces.
